HAND COVERING

Carroll P. Krupp, Akron, Ohio, assignor to The
B. F. Goodrich Company, New York, N. Y., a
corporation of New York

Application October 17, 1942, Serial No. 462,346

16 Claims. (Cl. 2—166)

This invention relates to flexible hand coverings and especially to inflatable gloves suitable, for example, for use by aviators with inflatable suits during flight at high altitudes.

The personnel of the high flying aircraft may be protected against the harmful physiological effects, such as "bends," of low pressure and oxygen deficiency by inflatable suits having flexible walls and which completely incase the wearer. Heretofore, it has been difficult to secure desirable freedom and flexibility of movement of the hands of the wearer of such suits; since the flexible walls of the hand covering portions resist bending and flexing when distended through inflation, the inflated article tending to approach a spherical shape.

Objects of the invention are to provide for effectively protecting the hands together with extensive freedom of movement while the covering is inflated, to provide a covering which is flexible and adapted for bending at lines of natural flexure of the palm of the hand, and to provide for simplicity of construction and convenience and ease of operation.

Other objects of my invention are to provide for resisting movement of the flexible hand covering away from the palm while permitting bending of the hand, and to provide for reinforcing the covering at the hinging zone between the finger and the palmar portions.

Specific objects of the invention are to provide for detachably connecting a glove to an inflatable suit, to provide for convenience in donning the glove, and to provide for ease of bending the glove, when under inflation, while preventing bulging of the dorsal and palmar portions of the same.

These and other objects and advantages of the invention will be apparent from the following description.

In the accompanying drawing which forms a part of this specification and in which like numerals are employed to designate like parts throughout the same,

Fig. 1 is a plan view of the back of a left hand glove constructed in accordance with and embodying the invention, parts being broken away and in section,

Fig. 2 is a plan view of the front of the glove, parts being broken away and in section,

Fig. 3 is a sectional view taken along line 3—3 of Fig. 1, and

Fig. 4 is a sectional view taken along line 4—4 of Fig. 2.

In the attainment of the objects of the inven-

tion a flexible hand covering 10 or glove is provided, suitable for use with an inflatable suit, and which conforms to the surface of the hand without undue outward bulging while under inflation.

5 The glove 10 is also manipulatable without objectionable effort by the wearer, when the hand is bent while performing sundry operations such as manipulating the controls of an aircraft.

To these ends, in the arrangement shown in 10 the illustrative embodiment of the invention in Figs. 1 and 2, the hand covering 10 is of flexible, fluid-tight material, such as rubber or other rubber-like material which may have a fabric reinforcement or lining. Bracing elements 11 to 14

15 inclusive, preferably of wire, disposed in a palmar portion 15 of the glove 10 in the manner shown prevent undue outward bulging and movement of the flexible material away from the palm while permitting bending of the hand.

20 In Figs. 1 and 2 the glove 10 comprises finger 21 to 25, palmar 15, dorsal 16, and gauntlet 17 portions interconnected in a fluid-tight manner, and, preferably, so formed that when in normal position, the hand assumes a naturally bent condition thus facilitating further bending of the glove by the hand while grasping an object. These portions may have a stockinet fabric lining 18 and 19 for greater strength to resist tear and expansion, when under internal pressure.

25 For convenience of manufacture the gauntlet portion 17 may be attached to the other portions 15, 16 of the glove at the wrist or carpal area 17a by an overlapping joint and a suitable adhesive like rubber cement, as shown in Fig. 4. The 30 gauntlet may, for greater strength, be made of square woven fabric coated or impregnated with a rubber or rubber-like material and having a stockinet fabric lining 19 adhered thereto as by a rubber cement.

35 The operation of bending an inflatable glove, when distended under internal pressure, is rendered especially difficult by bulging of the palmar and dorsal portions. My invention provides for desirable freedom of manipulation by means of 40 reinforcing strip elements 11 to 14 which prevent objectionable bulging of the palmar and dorsal portions 15 and 16 of the glove 10 and which confine bending of the palmar portion 15 to lines of natural flexure of the palm of the hand. The re-

45inforcing elements 11 to 14, preferably of steel wire, are disposed in the palmar portion 15 at the hinging zone between the finger 21 to 25 and palmar 15 portions in the manner shown in Figs. 1 and 2.

The spaced-apart wires 11 and 12 extend from

the margin of the dorsal portion 16 at the radial side of the hand adjacent the second metacarpal-phalangeal or index finger joint, and along the palmar portion 15 at points corresponding to the second to the fifth (little finger) metacarpal-phalangeal joints and at points corresponding to the distal third of the second to the fifth metacarpal bones of the palm, and continue to the margin of the dorsal portion 16 at the ulnar side of the hand adjacent the fifth metacarpal-phalangeal joint.

A third wire 13 extends along the dorsal portion 16 at the radial side of the hand following the interosseous area between the first (thumb) and the second metacarpal-phalangeal joints, and along the palmar portion 15 at the base of the thenar eminence of the thumb, and continues to the dorsal portion 16 at the radial side of the hand adjacent the first metacarpal joint.

For preventing bulging of the hypothenar area of the palmar portion 15, it is desirable to provide the wire 14 which is hingedly connected at 28 to the wire 13 at the base of the thenar eminence in the region of the interosseous area between the first and the second metacarpal bones of the hand. This wire 14 extends along the palmar portion 15 diagonally across the hypothenar area of the palm and continues along the dorsal portion 16 to the fifth metacarpal joint at the ulnar side of the hand.

Preferably, the wires 11 to 14 are shaped to conform generally to the contour of the hand at the lines of flexure, before attachment to the glove 10. The wires are disposed between a rubber covering 20 and the fabric lining 18 of the palmar and dorsal portions 15 and 16 and are sewed as at 29 to the lining, although the wires may be cemented in place by a rubber cement, for example.

Fabric patches 26 and 27 which are adhered to the lining 18 by a suitable adhesive such as rubber cement, prevent abrasion of the lining 18 by curved ends 11a, 12a, 13a, and 14a of the wires 11 to 14 and by a hinged connection 28 between the wires 13 and 14. Retaining strips 30, 31 and 32 of rubber or rubber-like material are superimposed upon the wires as shown in Figs. 1, 2, and 4, and are adhered in place as by a rubber cement.

From the foregoing description, it will be apparent that the arrangement of the bracing wires 11 to 14 effectively prevents undue bulging and movement of the palmar portion 15 away from the palm of the hand while permitting bending of the hand. These wires also assist in resisting undue bulging of the dorsal portion 16 by virtue of their end portions being disposed in the margins of the dorsal portion 16.

Additional resistance to bulging of the dorsal portion 16 is provided by a bellows structure 35 which seals and closes a slit 36 in the dorsal and gauntlet portions 16 and 17. Furthermore, the slit and the bellows structure permit outward extension of the walls of the glove 10 at the wrist enabling the admittance of the hand therethrough while providing for a snug fit at the wrist 17a.

As illustrated in Figs. 1 and 3, a bellows element 37 of rubber or rubber-like material 37a having a stockinet lining 37b and a separable fastener 38, preferably of the slide fastener type, are attached at the margins of the slit 36 by a suitable adhesive, such as rubber cement. A reinforcing cover strip 39 of rubber or woven fabric coated or impregnated with rubber-like material is superimposed upon the margins of the bellows element 37 and the fastener 38 at the margins of the slit 36, and adhered in position by a rubber

cement or other suitable adhesive. The glove 10 may be united as an integral unit by vulcanization.

The gauntlet portion 17 terminates at the elbow in an opening 40 for admitting the hand, and the glove 10 may be attached at the margin of the opening 40 to an elbow joint mechanism 41 for an inflatable suit in a manner such as is disclosed in my copending application Serial No. 445,016.

10 In donning the glove 10 with the slide fastener 38 being in the disengaged condition, the hand is inserted in the opening 40 and the glove is drawn toward the elbow, the hand sliding freely through at the wrist or carpal area 17a into position in the palmar, dorsal, and finger portions 15, 16, 21 to 25 thereby assuming a naturally bent condition. The slide fastener is then closed by moving a runner 38a to the position shown in Fig. 1 thus causing the walls of the glove to snugly fit the wrist of the wearer. The glove 10 is next attached to the elbow joint mechanism 41 as noted above.

When the glove 10 is united with the inflatable suit and under internal pressure, the walls of the glove are distended; nevertheless manipulation by the wearer is easily accomplished. The finger portions 21 to 25 may be flexed without objectionable resistance; since they are of relatively small extent as compared to that of the palmar and dorsal portions 15 and 16.

30 Maximum freedom of bending of the palmar portion 15 with a minimum of effort is achieved through the disposition of the reinforcing or bracing wires 11 to 14 in the palmar portion at lines of natural flexure of the palm of the hand. These wires function to prevent undesirable bulging and movement of the palmar portion 15 away from the palm while permitting easy bending of the hand. Coincidentally, the wires 11 to 14 together with the bellows structure 35 resist bulging of the dorsal portion.

35 Variations may be made without departing from the scope of the invention as it is defined in the following claims.

40 I claim:

1. A flexible hand covering comprising a body including rubber-like material having a flexible palmar portion and relatively stiff strip bracing means disposed in the material of said portion at lines of natural flexure of the palm of the hand for resisting movement of said portion away from the palm while permitting bending of the hand.

2. A flexible hand covering comprising a body including rubber-like material having a flexible palmar portion and elongated metal bracing elements in the material of said portion and extending along lines of natural flexure of the palm of the hand for resisting movement of said portion away from the palm while permitting bending of the hand.

3. A flexible hand covering comprising interconnected finger, dorsal, palmar portions, and elongated bracing elements disposed in the palmar portion for resisting movement of the palmar portion away from the palm of the hand while permitting bending of the hand, said elements extending along the hinging zone between the finger and palmar portions and comprising wires, and retaining strips of rubber-like material upon said wires.

4. A flexible hand covering comprising interconnected finger, dorsal, and palmar portions, and strip elements of stiff material disposed in the palmar portion along lines of natural flexure of the palm of the hand for resisting movement

of the palmar portion away from the palm while permitting bending of the hand.

5. A flexible hand covering comprising interconnected finger, dorsal, and palmar portions, and strip reinforcing elements of stiff material disposed in the palmar portion for resisting movement of the palmar portion away from the palm of the hand while permitting bending of the hand, said strip elements extending along the hinging zone between the finger and palmar portions and across the hypo-thenar area of the palm toward the wrist at the ulnar side of the hand.

6. A flexible hand covering comprising interconnected finger and thumb, dorsal, and palmar portions, and strip bracing elements of stiff material disposed in the palmar portion for resisting movement of the palmar portion away from the palm of the hand while permitting bending of the hand, said strip elements extending along the metacarpal-phalangeal joints of the fingers, along the base of the thenar eminence of the thumb, and across the hypo-thenar eminence of the palm toward the wrist at the ulnar side of the hand.

7. A flexible hand covering comprising interconnected finger and thumb, dorsal, and palmar portions, and strip bracing elements of stiff material disposed in the palmar portion for resisting movement of the palmar portion away from the palm of the hand while permitting bending of the hand, said strip elements comprising a pair of spaced-apart elements extending along the metacarpal-phalangeal joints of the fingers, and a bifurcated element extending along the base of the thenar eminence of the thumb and diagonally from the interosseous area between the first and second metacarpus across the hypo-thenar eminence of the palm in the direction of the fifth carpal-metacarpal joint.

8. A flexible hand covering comprising interconnected finger and thumb, dorsal, and palmar portions, and strip bracing elements of stiff material disposed in the palmar portion for resisting movement of the palmar portion away from the palm of the hand while permitting bending of the hand, said strip elements comprising a pair of spaced-apart elements each extending along the metacarpal-phalangeal joints of the fingers, a third element extending along the base of the thenar eminence of the thumb, and a fourth element hingedly connected to said third element in the interosseous area between the first and second metacarpus and extending diagonally across the hypo-thenar area of the palm in the direction of the fifth carpal-metacarpal joint.

9. A flexible hand covering comprising a flexible palmar portion and reinforcing elements of wire disposed in said portion at lines of natural flexure of the palm of the hand for resisting movement of the palmar portion away from the palm while permitting bending of the hand.

10. A flexible hand covering comprising interconnected finger, dorsal, and palmar portions, and reinforcing elements of wire disposed in the palmar portion for resisting movement of the palmar portion away from the palm of the hand while permitting bending of the hand, said elements extending along the hinging zone between the finger and palmar portions and diagonally across the hypo-thenar area of the palm toward the wrist at the ulnar side of the hand.

11. A flexible hand covering comprising interconnected finger and thumb, dorsal, and palmar portions, and reinforcing elements of wire dis-

posed in the palmar portion for resisting movement of the palmar portion away from the palm of the hand while permitting bending of the hand, said reinforcing elements comprising a pair of spaced-apart wires extending along the metacarpal-phalangeal joints of the fingers, and a bifurcated wire extending along the base of the thenar eminence of the thumb and diagonally from the interosseous area between the first and second metacarpus across the hypo-thenar eminence of the palm in the direction of the fifth carpal-metacarpal joint.

12. A flexible hand covering comprising interconnected finger and thumb, dorsal, and palmar portions, and reinforcing elements of wire disposed in the palmar portion for resisting movement of the palmar portion away from the palm of the hand while permitting bending of the hand, said reinforcing elements including a wire extending along the metacarpal-phalangeal joints of the fingers, a wire extending along the base of the thenar eminence of the thumb, and a wire hingedly connected to the second said wire at the interosseous area between the first and second metacarpus and extending across the hypo-thenar eminence of the palm in the direction of the wrist at the ulnar side of the hand.

13. A hand covering for an inflatable suit and capable of manipulation when under pressure, said covering comprising interconnected finger, dorsal, and palmar portions of fluid-tight flexible material and terminating in an opening for admitting the hand, elongated reinforcing elements disposed in the palmar portion at lines of natural flexure of the palm of the hand for resisting bulging of the palmar portion while permitting bending of the hand, and means for connecting said hand covering at said opening to an arm portion of an inflatable suit.

14. A glove for an inflatable suit and capable of manipulation when under pressure, said glove comprising interconnected finger and thumb, dorsal, and palmar portions of fluid-tight, flexible material and terminating in an opening for admitting the hand, bracing elements of wire disposed in the palmar portion for resisting bulging of the palmar portion while permitting bending of the hand, said bracing elements including a wire extending along the metacarpal-phalangeal joints of the fingers and a bifurcated wire extending along the base of the thenar eminence of the thumb and from the interosseous area between the first and second metacarpus across the hypo-thenar eminence of the palm in the direction of the wrist to the fifth carpal-metacarpal joint, and means for connecting said glove at said opening to an arm portion of an inflatable suit.

15. A glove for an inflatable suit capable of manipulation when under pressure, said glove comprising interconnected finger and thumb, dorsal, palmar, and gauntlet portions of fluid-tight, flexible material, the gauntlet portion terminating in an opening in the region of the elbow for admitting the hand, reinforcing wires disposed in the palmar portion for resisting bulging of the palmar portion while permitting bending of the hand, said wires comprising a pair of spaced-apart wires extending along the metacarpal-phalangeal joints of the fingers, a third wire extending along the base of the thenar eminence of the thumb, and a fourth wire hingedly connected to said third wire and extending from the interosseous area between the first and second metacarpus across the hypo-thenar eminence of the palm of the hand to the fifth carpal-metacarpal

joint, and means for connecting said glove at said opening to an arm portion of an inflatable suit.

16. A glove for an inflatable suit adapted to be manipulated when under pressure, said glove comprising interconnected finger and thumb, dorsal, palmar, and gauntlet portions of fluid-tight flexible material, the gauntlet portion terminating in an opening at the elbow for admitting the hand, a slotted aperture in the gauntlet and dorsal portions extending along the gauntlet for facilitating insertion and withdrawal of the hand, a bellows element secured to the margin of said aperture for sealing the latter and for stiffening the dorsal portion against bulging, separable fastener means for closing the slotted aperture, reinforcing wires embracing the radial and ulnar sides of the hand

and disposed in the palmar portion for resisting movement of the palmar portion away from the palm of the hand while permitting bending of the hand, said wires comprising a pair of spaced-apart wires extending along the metacarpal-phalangeal joints of the fingers, a third wire extending along the base of the thenar eminence of the thumb, and a fourth wire hingedly connected to said third wire and extending from the interosseous area between the first and second metacarpus across the hypo-thenar area of the palm to the fifth carpal-metacarpal joint, and an annular means for connecting said glove at said opening to an arm portion of an inflatable suit.

15

CARROLL P. KRUPP.
